UNITED STATES PATENT OFFICE.

ELDRIDGE J. SMITH, OF TITUSVILLE, PENNSYLVANIA.

SWING.

SPECIFICATION forming part of Letters Patent No. 307,811, dated November 11, 1884.

Application filed June 26, 1884. (No model.)

To all whom it may concern:

Be it known that I, ELDRIDGE J. SMITH, a citizen of the United States, residing at Titusville, in the county of Crawford and State of Pennsylvania, have invented certain new and useful Improvements in Swings; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a view in perspective of my swing. Figs. 2 and 3 are detail views. Fig. 4 is a sectional detail view. Figs. 5 and 6 are detail views.

This invention has relation to improvements 20 in swings; and it has for its object to provide a cheap and simple means for bracing the frame and preventing the joints from spreading or moving apart. Another end in view is to provide the backs and seats of the carriage 25 with sufficient spring or elasticity to assist the occupants in propelling the swing.

Referring by letter to the accompanying drawings, A indicates the swing-supporting frame, which consists, essentially, of the vertically-inclined beams a, which are properly braced at their lower ends, and the transverse horizontal beam B, which is firmly secured between the adjacent upper ends of the said beams a, as shown. The horizontal cross-beam B is 35 provided on its under side, near opposite ends, with vertically-depend ing lugs b, the outer walls of which are plain, as shown, to receive the cross-arms C C. These cross-arms are beveled on their outer longitudinal sides, as at c, 40 to conform to the inclination of the supporting-beams a, to which they are respectively bolted, as shown at d, thus making the horizontal cross-beam, the cross-arms, and vertically-inclined beams a rigid with relation to each other.

45 D indicates the parallel swing-bars, which are pivotally suspended at their upper ends from the outer ends of the cross-arms C C, and connected at their lower ends to the carriage, 50 as will be presently explained.

E indicates the carriage, which is made in two sections, e e, each section being provided

with an elastic back and seat, g, which may be formed of slats strung upon wires and separated by coils of similar material. The fabric thus formed, being provided at opposite ends with rounds h, is let into the opposite side walls, k, of the carriage. These side walls, k, are recessed or shouldered, as shown at l, to engage each other, and are connected by a vertical bolt, m, which may extend down and through a cleat or strip of suitable material on the under side of the carriage, and up through a longitudinal bar, F, which is provided with shoulders n n, to engage shoulders 65 on the upper edges of the side walls, k. The lower ends of the suspended swing-bars are connected by a pivot-bolt to the opposite ends of the bars F. By this construction it will be perceived that the joints of the seat are made 70 very substantial, and, from the peculiar construction of the connecting parts, strain is removed from the weakest portion of the carriage.

Having thus described my invention, what I 75 claim as new, and desire to secure by Letters Patent, is—

1. In a swing, the combination, with the vertically-inclined beams a, of the horizontal cross-beam B, having the depending lugs b, 80 and the cross-arms C C, having their outer sides beveled, as shown, and secured to the said beams a, substantially as specified.

2. The swing-carriage consisting of the parts e e, having their side walls, k, provided with 85 the recesses l l, and their edge walls with the recesses, the longitudinal shouldered bars F, cleats, and bolts for connecting the same, substantially as specified.

3. The swing described, consisting of the 90 vertically-inclined beams a, the horizontal cross-beam B, the cross-arms C C, having their outer longitudinal sides inclined, the parallel suspended swing-bars D, pivoted at the outer ends of the arms C, and at the lower ends to 95 the carriage, and the carriage formed of the sections e e, having the elastic seats and backs, substantially as specified.

In testimony whereof I affix my signature in presence of two witnesses.

ELDRIDGE J. SMITH.

Witnesses:

PHILIP C. MASI,
